Primary Examiner — Brett Miller*Assistant Examiner* — Rani J Abdallah(57) **CLAIM**

The ornamental design for an oats jar, as shown and described.

DESCRIPTION

FIG. 1 is a front, top perspective view of an oats jar, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in a position of use; and,

FIG. 10 is an enlarged view of detail “10” identified in FIG. 2.

The dash dot dash lines in FIGS. 2 and 10 are for the purpose of illustrating the enlarged view indicators and form no part of the claimed design. The evenly dashed lines are shown for the purpose of illustrating both parts of the oats jar as well as environmental subject matter. None of the dashed lines form part of the claimed design.
